UNITED STATES PATENT OFFICE.

GEORGE H. COLDWELL, OF ROCKTON, PENNSYLVANIA.

GATE FOR SPLASH-DAMS.

SPECIFICATION forming part of Letters Patent No. 392,499, dated November 6, 1888.

Application filed March 23, 1888. Serial No. 268,263. (No model.)

To all whom it may concern:

Be it known that I, GEORGE H. COLDWELL, a citizen of the United States of America, residing at Rockton, in the county of Clearfield and State of Pennsylvania, have invented certain new and useful Improvements in Gates for Splash-Dams, of which the following is a specification, reference being had therein to the accompanying drawings.

10 This invention pertains to certain new and useful improvements in gates or draws for splash-dams, having reference more particularly for use in connection with a dam on which logs are floated.

15 The invention has for its object the production of simple and highly-efficient means for opening the gate or draw at the desired time as regulated by the amount of water contained within the upper portion of the dam or creek, 20 the opening of said gate or draw being regulated by the movement of a float.

25 The invention comprises the detail construction, combination, and arrangement of parts, substantially as hereinafter fully set forth, and particularly pointed out in the claims.

In the accompanying drawings, Figure 1 is a front elevation of my invention. Fig. 2 is a rear view thereof. Fig. 3 is a plan view. Fig. 4 is a side view, and Fig. 5 is a detail view.

30 Referring to the drawings, A. A designate two uprights or slightly-inclined bars connected at their lower ends to a transverse bar, a , to which are secured two outwardly-projecting bars, a' a' , and a third outwardly-projecting bar, a^2 . The uprights or bars are connected to the bars a by two parallel inclined bars, a^3 a^4 , as shown. To the front edges of the uprights or bars A is secured a horizontal bar, a^5 , supported at one end by a short post or upright, a^6 , secured to the transverse bar a , as shown, and within the space between the post a^6 and the adjacent upright or bar A is placed a partition, b , in the lower portion of which is formed an opening, b' , having grooves or recesses b^2 in its sides.

45 B is a sliding gate or draw designed to fit at its end between guide-bars b^3 b^4 , secured to the rear edges of the uprights or bars A. To this gate or draw are secured two pulleys, b^4 b^5 , around which are passed ropes or chains b^6 , connected at their inner ends to a transverse

rod, C, resting in the uprights or bars A, and said ropes or chains are passed over grooved pulleys b^6 b^7 , secured on said transverse rod, and from these said ropes or chains are passed down and secured to a revolving shaft, D, resting on suitable journal-boxes, d d , attached to the inclined bars a^3 . To one end of the shaft D is secured a cog-wheel or pinion, d' , gearing with the small cog-wheel or pinion d^2 , fast 60 upon the shaft d^3 of the water-wheel d^1 , the ends of said shaft d^3 being secured in suitable journal-boxes attached to one of the inclined bars a^3 and to a short supporting-post, d^4 , secured to the outwardly-projecting bar a^2 . By turning the water-wheel d^1 the gate or draw B can be raised or lowered.

E is a revolving gate secured upon the lower end of the vertical rod or spindle e , which is projected up through the board or partition b and through the horizontal bar a^5 . To the upper end of this vertical rod or spindle e is secured one end of an approximately V-shape locking-plate, F, to the end of one arm of which is secured a rope or chain, f , which is passed 75 over a pulley, f' , pivoted in a groove or recess in the horizontal bar a^5 , and has secured to its outer end a weight, f^2 . To this arm is also secured a rope or chain, f^3 , passed through a guide-staple, f^4 , and attached to a stud or pin 80 of a lever, f^5 , fulcrumed at one end to the side of one of the uprights or bars A, and with this lever is designed to come in contact a stud or pin, f^6 , projecting from the gate or draw B.

G is a lever fulcrumed at one end to an apertured arm, g , of the frame a , and to this lever is connected a small trigger or trip, g' , and upon the rear portion of this are adjustably secured the upwardly-projecting arms g^2 g^3 of a float, H. The arms g^2 g^3 have a series of 90 holes or apertures therein, wherein transverse pins h h' are designed to fit, and said pins hug the upper and lower edges of the lever G.

In practice the gate or draw B is lowered while the upper portion of the dam or creek 95 is being filled or supplied with water, and the gate or door E is closed against the grooved sides of the opening b' . When sufficient water has been gathered or collected in said upper portion of the dam or creek, the same 100 through the agency of the float H raises the lever G, causing the disengagement of the trig-

ger or trip *g* from the arm *F'* of the V-shape locking-plate *F*, which will permit the same to move by reason of the weight connected to the other arm thereof, causing, through the agency of the vertical rod or spindle *e*, the partial revolution of the gate *E*, which will now occupy a position at right angles to that previously described. This opening of the gate *E* permits the inflow of water through the opening *b*, which will strike against the water-wheel, causing the revolution thereof in the direction of the arrow *w*, which will effect the revolution of the shaft *D* and the winding thereon of the ropes or chains, causing the elevation of the gate or draw *B*, thus permitting the water and logs to float between the uprights or bars *A*.

The gate or draw *B* in its elevation will effect the rising of the lever *f⁵*, which will pull on the rope or chain *f³*, drawing the locking-plate *F* to its former position as against the action of its weight, thereby when water is lowered the desired extent in the upper portion of the draw or creek causing the lowering of the float *H*. The lever *G*, together with its trigger or trip *g*, will be lowered, causing said trigger or trip to come in contact with the outer end of the arm *F'* of said locking-plate, and such turning of the locking-plate to its former position will effect the closing of the gate *E*, thereby cutting off the supply of water, and consequently causing the revolution of the water-wheel to cease. When it is desired to again lower the gate or draw *B*, the same is effected by the operator revolving the water-wheel in the direction opposite to that previously described.

From the foregoing description it will be seen that the amount of water to be gathered in the upper portion of the dam or creek before the gate or draw is opened can be regulated by means of the pins in the arms of the float *H*, the movement of such float causing the raising of the lever *G*, and permitting the opening of the gate *E* and allowing the inflow of water onto the water-wheel.

I claim as my invention—

1. As an improvement in gates or draws for splash-dams, the V-shape locking-plate, the vertical rod or spindle, the revolving gate, and the lever having the trigger or trip, substantially as shown and described. 50

2. As an improvement in gates or draws of the class herein described, the V-shape locking-plate having a weight connected to one end thereof, the revolving gate secured on the spindle or rod of said locking-plate, the lever having a rope or chain connecting the same to said locking-plate, the lever having the trigger or trip and the sliding gate or draw, substantially as shown and described. 55

3. The combination, with the uprights or bars and the transverse rod having the grooved pulleys, of the sliding gate or draw, the ropes or chains passed over pulleys thereof, the 65 shafts, the pinions or gear-wheels, the water-wheel, and the revolving gate, substantially as shown and described.

4. The combination, with the sliding gate or draw and the water-wheel operating the same, 70 of the revolving gate, the V-shape locking-plate, the lever having the trigger or trip, and the float connected to said lever, substantially as shown and described.

5. The combination, with the sliding gate or draw and the water-wheel operating the same, 75 of the revolving gate, the locking-plate, the lever having the trigger or trip, the weight connected to said locking-plate, and the lever operated upon by said gate or draw and connected to said locking-plate, substantially as shown and described. 80

6. The combination, with the revolving gate and the V-shape locking-plate, of the lever having the trigger or trip, and the float having the arms provided with a series of apertures, and the transverse rod or pin, substantially as shown and described. 85

In testimony whereof I affix my signature in presence of two witnesses.

GEORGE H. COLDWELL.
